Primary Examiner—Alan P. Douglas*Assistant Examiner*—R. Spear*Attorney, Agent, or Firm*—Jeffrey T. Imai; Arne I. Fors; D. Doak Horne[57] **CLAIM**

The ornamental design for an adhesive bottle cap, as shown and described.

DESCRIPTION

FIG. 1 is a perspective view of my design for an adhesive bottle cap;

FIG. 2 is a front elevational view of the design of FIG. 1, the rear, right and left elevational views being identical thereto;

FIG. 3 is an elevational view of the design of FIG. 1 rotated 45° from FIG. 2; and,

FIG. 4 is a top plan view of the design of FIG. 1. The broken line showing of an adhesive bottle is for illustrative purposes only and forms no part of the claimed design.

FIG.1.

FIG.2.

FIG.3.

FIG.4.
